UNITED STATES PATENT OFFICE.

EDMOND BRUCE, OF RED BANK, NEW JERSEY, ASSIGNOR TO WESTERN ELECTRIC COMPANY, INCORPORATED, OF NEW YORK, N. Y., A CORPORATION OF NEW YORK.

ELECTRIC-WAVE-TRANSLATION SYSTEM.

Application filed August 8, 1925. Serial No. 48,988.

This invention relates to electric wave translation systems, and more particularly to improved coupling arrangements for coupling local oscillators to heterodyne radio receiving systems.

In radio receiving systems wherein a local oscillator is employed to supply combining oscillations for reducing the frequency of the incoming wave to a desired lower frequency level, it is very desirable to prevent the radiation from the receiving antenna of waves generated by the oscillator. This is to be desired, because of the likelihood of causing serious interference with nearby receiving sets.

When using a radio receiver of the type referred to above and including a local oscillator directly coupled to the antenna circuit, it is also often desirable to be able to adjust the tuning of the antenna, such as a loop antenna, without varying the amount of energy, supplied by the local oscillator to the detector. A specific instance where it is important to be able to accomplish this is in receiving systems employed for field strength measurements. If the receiving circuit is such that the oscillator voltage varies with changes in tuning of the antenna, the circuit will be of little use for field strength measurements because erroneous readings are likely to be obtained. This results from the fact that the intermediate frequency voltage in a heterodyne circuit is substantially proportional to the product of the voltage of received waves and the voltage of the locally supplied waves. It is, therefore, clear that if the voltage of local waves is varied by the tuning of the receiving circuit, the maximum voltage of the intermediate frequency waves may occur when the receiving circuit is tuned to a frequency other than the frequency of received waves. This will be evident from the fact that when the tuning of a receiving circuit is varied, the change in its admittance for received waves may be different from its change of admittance for locally supplied waves.

It is an object of this invention to prevent waves from being radiated from a receiving antenna.

Another object is to prevent changes in tuning of a receiving circuit from affecting the voltage of waves supplied by a local oscil-

lator to a space discharge repeater associated with the receiving circuit.

Another object is to transmit signal waves and local oscillations to a space discharge device over an adjustable resonant path without changing the value of its admittance for local oscillations when the tuning of the resonant path is varied.

An additional object is to prevent erroneous indications of the voltage of received waves.

A feature of the invention is a balanced coupling arrangement of an antenna, oscillator and detector.

A further feature is a balanced coupling device so associated with an oscillation generator, a detector, and a receiving circuit that the tuning of the receiving circuit will have no effect upon the voltage of local oscillations supplied to the detector.

A further feature is a transformer having windings included in a closed receiving circuit and another winding coupled thereto and included in a local oscillator circuit.

A still further feature is a space discharge tube detector including a path for balancing the inherent reactive path through the tube and having a receiving circuit and an oscillator associated with the tube in such manner as not to disturb the balance of the circuit, whereby the tuning of the receiving circuit may be varied without affecting the voltage of waves supplied by the oscillator to the detector.

The invention relates broadly to electric wave translation systems including a variable impedance or variable admittance path for transmitting a plurality of different waves from separate sources to a common receiving device. Certain elements of the system are adapted to permit waves from one of the sources to traverse the variable path without having their voltage changed as a result of variations in the admittance of the path.

For practical use, the invention may be embodied in a radio receiving system of the type employing local oscillators for receiving by the heterodyne method. The variable path may be a resonant receiving circuit, including for example, a loop antenna and certain windings of a balanced transformer. Other windings of this transformer

may be included in appropriate circuits of a space discharge tube for the generation of oscillations as well as for transmitting these oscillations through the receiving circuit to another space discharge tube, which may be a detector.

Signal waves impressed upon the receiving circuit may be combined with local oscillations in the detector to produce an intermediate frequency wave. The voltage of the intermediate waves may represent the voltage of received waves, since the locally generated waves are supplied to the detector in such manner that their voltage is unaffected by adjustments made in the tuning of the receiving circuit. This circuit will ordinarily be tuned to the frequency of received waves.

In Fig. 1 of the drawings, the invention is illustrated in connection with a heterodyne radio receiving system.

In Fig. 2 a modification of the circuit of Fig. 1 to the left of the dotted line $\alpha-\alpha$ is illustrated.

The radio receiving circuit shown in Fig. 1 of the drawing includes an antenna 10, in this instance illustrated as a loop antenna; a heterodyne oscillator 20, a balanced coupling transformer 13, a high frequency detector 30, an intermediate frequency amplifier 40, a low frequency detector 50 and a low frequency amplifier 51. The loop antenna 10 has its outer terminals connected to an adjustable tuning condenser 11. One outer terminal is also connected to the control electrode of space discharge tube 31. The other outer terminal is connected to the ground through the condenser 32 which is adapted to balance the effective input capacity of the discharge device 31, whereby the high frequency receiving circuit is rendered symmetrical with respect to the oscillator 20.

At the mid-point of loop antenna 10 the secondary windings 12 of the balanced transformer 13 are serially included, and the mid-point of these windings is connected to ground and thence to the cathode of tube 31 by way of the cathode of the tubes 52, 21, 53, 42, and 41. A suitable potential is applied to the control electrode of tube 31 by the drop in potential along the filaments just mentioned. The primary windings 14 and 15 of transformer 13 which are arranged in balanced relation to the windings 12 are included separately in the input and output circuits of the space discharge tube oscillator 21. These windings have one terminal of each connected to the control electrode and anode respectively of tube 21. The input circuit of tube 21 is traceable from its control electrode through winding 14 to ground thence to the cathode of tube 21, via the cathode of tube 52. A suitable polarizing potential is supplied to the control electrode of the tube 21 by the drop in potential along the filament of tube 52.

The output and space current circuit for tube 21 may be traced from the anode to transformer winding 15, to the positive pole of the space current battery 54 to ground at its negative pole, thence to the cathode 70 of the tube over the path already traced.

A resonant circuit, for determining the frequency of oscillations generated in space discharge tube 20, is provided by the adjustable condenser 22 connected between the control electrode and cathode in conjunction with the mutual and self-inductance of the windings of transformer 13.

The space discharge tube 31 has an output circuit connected to its anode including the primary winding of transformer 33 (shunted by adjustable resistance 34) arranged in series with the space current battery 54, the opposite terminal of which is connected to the cathode of tube 31. The output circuit of tube 31 is coupled to the input circuit of intermediate frequency amplifier 40 by transformer 33. The amplifier 40 includes the two space discharge tubes 41 and 42. The output circuit of tube 42 is coupled to the input circuit 90 of a second detector 50, including the space discharge tube 52 having a suitable blocking condenser and grid leak resistance 55 included in its input circuit. The output circuit of tube 52 is coupled to an audible frequency amplifier tube 53 having suitable output terminals 56 and 57 for connection to any desired device such as telephone receivers, loud speaking receiver, a wire line or the like.

Condensers 35 and 36 are provided to supply low impedance paths for high frequency waves around the space current source 54 in one case, and around the filaments of tubes 52, 21, 53, 42 and 41 in the other.

The secondary windings 12 of the coupling transformer 13 may be constructed by merely twisting together a short length of the loop conductors at the points where the windings 12 are shown connected or they may be ordinary solenoidal windings arranged to be inductively coupled. The primary windings 14 and 15 may be suitably positioned with respect to the windings 12. For example they may be solenoids arranged coaxial with the windings 12.

By coupling the oscillator 20 to the loop antenna 10, which may also be an ordinary inductance to which, if desired, an open antenna may be coupled, at the point indicated, a balanced bridge arrangement results, the balance of which is independent of frequency. The current induced in windings 12 divides equally between the two halves of the loop antenna or inductance 10 so that no difference of potential is produced at the terminals 23 and 24 and hence, the magnitude of the voltage of waves supplied by the oscillator to the control electrode of tube 31 is independent of the adjustment of tuning condenser 11.

In order to further prevent an unbalance in the circuit, by virtue of any direct supply of waves from the oscillator to the antenna 10 by radiation, the oscillator is shielded 5 from the antenna and also from the tuning condenser. The latter is included in a separate shielding compartment. The rest of the receiving circuit is also included in a separate shielding compartment. The shield is 10 represented by the broken line 25.

When the circuit is in operation, radio waves of any sort may be received by antenna 10 and will establish a voltage therein. One 15 half of this voltage is applied to tube 31 between its control electrode and cathode, because these electrodes are connected between the mid-point and one terminal of the loop. Waves from oscillator 20, which preferably have a frequency differing from that of the 20 received wave, are also supplied to the input circuit of tube 31 and are combined with the received waves to produce intermediate frequency waves of inaudible but readily amplifiable frequency. The voltage of the intermediate frequency waves is substantially 25 proportional to the product of the voltages of received and locally supplied waves.

The intermediate frequency waves are detected in the second detector 50 and the detected current is amplified in the circuit including tube 53. At the terminals 56 and 57, low frequency waves are available and the voltage of these waves is proportional to the voltage or intensity of the waves received by antenna 10, because the voltage of local waves from oscillator 20 are constant and unaffected by the tuning of the loop.

In the coupling arrangement of the invention undesired capacity to ground effects 40 of the windings 12 of transformer 13 are avoided by the ground connection at the common terminal. By this connection also the loop circuit is stabilized as regards its capacity to ground.

Another advantage of the arrangement described is that the coupling transformer is substantially non-inductive in relation to the antenna and hence has no effect upon the resonance point of the receiving circuit.

By coupling the oscillator to the control electrode circuit instead of the plate circuit of tube 31, advantage is taken of the amplifying power of the tube and radiation of locally generated waves is prevented by the fact that these waves divide equally between the two halves of the loop antenna. No interference with other receiving circuits will therefore be produced.

In Fig. 2, a modification of the portion 60 of the circuit to the left of the dotted line $\alpha-\alpha$ on Fig. 1 is shown. This figure includes the antenna 10 with its tuning condenser 11, balanced transformer 14, oscillator 20 including the tube 21, and a portion of the amplifier tube 31. This circuit differs from

the corresponding portion of the circuit of Fig. 1 in that the right-hand secondary winding 12 of transformer 14 is not connected directly to ground, but by a path including the condenser 60 in series with the oscillation 70 generator 61. The condenser 60 and the generator 61 are shunted by an adjustable resistance 62. In all other respects the two circuits are identical.

The arrangement shown in Fig. 2 enables 75 a local oscillator 61 to supply waves for comparison or for calibration purposes and is adapted to permit the oscillator 61 to be connected to the circuit without causing unbalance thereof. This is accomplished by connecting the oscillator 61 to points corresponding to the points of connection of the terminals of the antenna 10. Waves are supplied by oscillator 61, at a time when no waves are being received by the antenna. The waves 80 from oscillator 61 are combined with waves from the oscillator 21 in the same manner as waves received on the antenna were combined therewith.

The adjustable resistance 62 is provided to 90 permit the amplitude of the oscillations supplied by the source 61 to be adjusted to a desired value. For example, the amplitude of an incoming signal wave may be measured by utilizing the source 61 to simulate the received wave. This is accomplished by supplying oscillations from the source 61 and adjusting the amplitude of the oscillations to such value that the output voltage at terminals 56 and 57 is the same for oscillations 95 from source 61 as for received waves. The amplitude of the oscillations supplied by source 61 being known, the amplitude of the received waves may be readily determined.

Switch 63 is provided to permit the winding 105 12 to be connected to ground for ordinary reception, or to the oscillator 61 for measurement or calibration purposes. It is to be noted that the auxiliary source 61 is connected to the terminal of the winding 12 110 which is normally grounded, whereby the balance of the receiving circuit is undisturbed when the source 61 is connected to the system.

For ordinary reception purposes the transformer 13 need only be provided with a single secondary winding 12 in place of the two windings illustrated in Fig. 1.

The arrangement is only illustrative of one embodiment of the many in which the invention may be incorporated. For example, the position of the coupling transformer may be modified without changing the principle of operation and other changes and embodiments will, of course, readily suggest themselves to persons skilled in the art, without 120 the exercise of any inventive effort. The limits of the invention are therefore defined only by the scope of the appended claims.

What is claimed is:

1. In combination, an inductance, a trans- 130

- former having windings included in series with said inductance, a connection to ground from a mid-point of said windings, a repeater having electrodes connected to outer terminals of said inductance, and an oscillation generator coupled to said windings for supplying waves to said repeater, the voltage of said waves being independent of the characteristics of said repeater circuit.
10. 2. In combination, a loop antenna, a space discharge repeater including electrodes connected to said antenna, a balanced transformer connected between said antenna and ground, and an oscillation generator symmetrically connected to said antenna to transmit waves through said antenna to said repeater, whereby the voltage of said waves is independent of changes in tuning of said antenna.
20. 3. In combination, an inductance, a variable condenser connected to outer terminals of said inductance, a space discharge repeater having electrodes also connected to said outer terminals, a transformer having two equal windings connected in series with said inductance at its electrical center, said windings having a common terminal connected to ground, other windings for said transformer, an oscillation generator including input and output circuits, said other windings being connected in said input and output circuits, said oscillator being in conjugate relation with respect to the path through said variable condenser.
30. 4. In combination, an antenna, an oscillation generator, a space discharge repeater coupled to said antenna, means for transmitting waves from said generator to said repeater, said means including said antenna and a transformer having windings in balanced relation thereto, said means being adapted to prevent radiation of waves from said antenna.
40. 5. In combination, a loop antenna having terminals, a space discharge tube including a cathode, anode and control electrode, a connection from one terminal of said antenna to said control electrode, a connection from another terminal of said antenna to ground through a condenser, a variable condenser connected across the terminals of said antenna, an oscillation generator, and means for coupling said generator to said loop in such manner as to produce no difference of potential at said terminals, said means comprising a transformer having windings included in said antenna circuit at its electrical mid-point.
6. In a radio receiving system, a loop antenna, a variable condenser connected to terminals of said loop, a space discharge repeater having electrodes connected in balanced relation to said loop and means for compensating the effective input capacity of said repeater, an oscillation generator, and means for coupling said generator to said repeater whereby the voltage of said oscillator is independent of said repeater circuit without affecting said balanced connection, said means including a four winding transformer having two secondary windings with a common terminal connected to ground.
7. In a radio receiving system, a space discharge oscillator and a space discharge repeater, a balanced transformer having two windings connected to said oscillator and two windings connected to said repeater, said pairs of windings forming elements of separate resonant circuits for said repeater and oscillator, and means whereby the tuning of said resonant circuit may be adjusted for said repeater without affecting the voltage of waves from said oscillator.
8. In a radio receiving system, a tuned oscillating circuit, an antenna circuit comprising a tuned loop, a transformer having windings in each of said circuits, a space discharge repeater having a cathode, an anode and a grid control electrode, a connection from one terminal of said loop to the grid control electrode, a connection from the other terminal of said loop to the cathode of said repeater, said last mentioned connection including a condenser for balancing the grid to cathode capacity of said repeater, and a connection from the mid-point of said antenna to ground.
9. In a heterodyne receiving system, a loop antenna, a repeater having an input circuit, an oscillator, means for coupling said oscillator to said antenna and to said input circuit, said antenna having a connection to ground at its mid-point and connections to ground including equal capacities from the terminals of said antenna.
- In witness whereof, I hereunto subscribe my name this third day of August, A. D. 1925.
- EDMOND BRUCE.
